UNITED STATES PATENT OFFICE.

ALFRED E. STAFFORD, OF HOPEDALE, MASSACHUSETTS, ASSIGNOR TO DRAPER CORPORATION, OF HOPEDALE, MASSACHUSETTS, A CORPORATION OF MAINE.

FILLING-END CONTROLLER.

Application filed May 14, 1925. Serial No. 30,241.

To all whom it may concern:

Be it known that I, ALFRED E. STAFFORD, a citizen of the United States, residing at Hopedale, in the county of Worcester and State of Massachusetts, have invented an Improvement in Filling-End Controllers, of which the following description, in connection with the accompanying drawings, is a specification, like characters on the drawings representing like parts.

This invention relates to filling replenishing looms wherein the filling is replenished from time to time.

When filling replenishment is effected, there is a spent filling end extending from the cloth selvage to the shuttle eye and thence into the shuttle and to the bobbin which is to be ejected and such filling end must be removed, otherwise it is liable to be carried into the shed on a subsequent pick of the shuttle and form imperfect cloth. Much attention and great inventive skill have been devoted to the spent filling end, and various means have been suggested and employed for this purpose.

It has been proposed, for instance, to cut and clamp the filling end adjacent the shuttle eye when the shuttle is in the replenishing box, so that the end leading towards the cloth selvage may be removed, while the end leading to the filling carrier or bobbin in the shuttle may pass backwardly through the shuttle eye with the bobbin when it is ejected. In this type of filling end controller it is usual to provide the shuttle with a recess near the shuttle eye, by removing a part of the shuttle wood, in order that the parter or parter and clamp may engage the filling.

It has been proposed, also, to engage the spent filling adjacent the feeler slot of the shuttle when in replenishing position and to withdraw the end longitudinally through the front wall of the shuttle box.

In accordance with the present invention, means are provided for engaging the spent filling at the feeler slot of the shuttle when in replenishing position and to withdraw the filling frontwardly about the cloth selvage as a center, in which case, of course, the usual shuttle feeler thread cutter is not employed, although in some instances it may be. In case the shuttle feeler thread cutter and clamp which is of usual construction, is employed, the present invention

contemplates that the end leading towards the cloth selvage and terminating at the shuttle feeler thread cutter and clamp, shall be withdrawn over the top of the shuttle box, but the preferred construction omits the shuttle feeler thread cutter and clamp and swings the spent filling end from a point adjacent the feeler slot outwardly relative to the front wall of the shuttle box and about the cloth selvage as a center, so that the spent filling end is positioned at the cloth selvage for the action of the usual temple thread cutter.

In carrying the invention into practical effect, the front wall of the shuttle box is provided with an open slot leading from the edge of the front wall at a point adjacent the feeler slot of the shuttle when the latter is in replenishing position, so that the filling end may be swung outwardly over the top of the front wall of the shuttle box and about the cloth selvage as a center.

The invention and new combination of parts will best be made clear from the following description and the accompanying drawings of one good practical form thereof.

In the drawings:

Fig. 1 is a perspective view of a loom at the replenishing side, provided with the present invention;

Fig. 2 is an enlarged detail showing one form of the thread parter and clamp to engage the spent filling at the feeler slot of the shuttle when in replenishing position and withdraw it outwardly about the cloth selvage as a center;

Fig. 3 is an enlarged sectional end elevation showing the relation of the parts at the time of replenishment of filling, with the thread parter and clamp acting upon the filling at the feeler slot of the shuttle;

Fig. 4 is an enlarged perspective view showing the front wall of the shuttle box provided with an open slot leading downwardly from the top thereof at a point adjacent the feeler slot of the shuttle, and the thread parter and clamp withdrawing the spent filling end over the top of the shuttle box about the cloth selvage as a center;

Fig. 5 is an enlarged detail showing more particularly the spent filling end as having been cut and held by the parter and clamp; and

Fig. 6 is a front elevation of details of

the mechanism for moving the thread parter and clamp to and from its thread engaging position.

In accordance with the present invention, 5 the spent filling end leading to the cloth selvage is removed outwardly from a point adjacent the feeler slot of the shuttle and about the cloth selvage as a center, in order to position the spent filling end at the cloth selvage 10 for the action of the temple thread cutter, all as will more fully appear.

The loom frame 1 is of usual construction and the breast beam 2 has mounted thereon the usual temple 3 provided with a temple thread cutter or selvage cutter 4 for severing the end of the filling on the cloth selvage. Mounted on the stand 5, which may be conveniently secured to the breast beam, is the hopper 6 for holding a series of filling carriers or bobbins 7 having a supply of filling wound thereon. The hopper 6 is shown as of the rotary type, but the invention is not restricted thereto, as any form of filling supplying hopper may be employed.

25 Extending from the hopper stand 5 is the arm or dead shaft 8 on which is mounted the transerrer 9, as usual. The transerrer 9 is normally under the influence of a spring 10 for maintaining it in raised or inoperative position, and extending downwardly from the transerrer 9 is the arm 11 having pivotally connected thereto the dog 12, the end of which is adapted to be engaged by a bunter 13 on the lay when filling replenishment is to be effected. These parts may be 30 of usual construction.

35 Mounted in bearings 14, one at each side of the loom, is the transverse or rock shaft 15 having secured thereto the rearwardly extending arm 16, as usual, which is normally under the influence of a spring 17, and connected to the arm 16 is the finger 18 which engages a pin 19 connected to the shuttle feeler 20, the construction being such 40 that when replenishment is called by rocking movement of the shaft 15, the shuttle feeler will be moved rearwardly into its position for determining whether or not the shuttle is properly boxed. The means for 45 rocking the transverse or rock shaft 15 when filling is to be changed is not illustrated, because such means is now well understood in the art and may comprise any well-known form of mechanism for this purpose.

50 As hereinbefore indicated, the preferred form of the invention contemplates that the spent filling end is to be parted at a point adjacent the feeler slot of the shuttle when in replenishing position, and the end thereof leading to the cloth selvage is to be engaged and held by a clamp which acts upon 55 replenishment to move the end leading to the cloth selvage over the top of the front wall of the shuttle box, as shown.

60 Secured to and extending downwardly

from the dead shaft 8, Fig. 1, is a frame or bracket 21 to which is secured by bolts 22 the guideway 23 of a sliding carrier 24 to which the thread parter and clamp are connected. In the present instance of the invention, the thread parter and clamp are carried by a lug 25 extending from the carrier or slide 24, as indicated in Fig. 2. The thread parter and clamp comprises the relatively fixed members 26, 27 between which is mounted on the pivotal support 28 the movable thread parter and clamp 29, the edge whereof towards the shuttle eye serves to part the spent filling that it may be drawn backwardly through the shuttle eye and 70 from the shuttle when the spent filling carrier or bobbin is ejected, and the face portion of the thread parter and clamp towards the cloth selvage is formed to clamp the end leading to the cloth selvage and swing the 75 end over the top of the shuttle box about the cloth selvage as a center. The particular construction of the thread parter and clamp forms no essential part of the present invention, the requisite being that the spent filling end shall be parted and clamped at a 80 point adjacent the feeler slot of the shuttle when in replenishing position, and that the end leading towards the cloth selvage shall be swung outwardly over the edge of the 85 shuttle box.

85 Loosely mounted on the dead shaft 8 is the carrier or slide operating member 31 the lower end portion of which is conveniently bifurcated at 32 for the reception of the pin 33 extending from the slide 24, and the operating member 31 is connected to the shuttle feeler, so that, as the shuttle feeler is moved rearwardly on call for replenishment of filling, the operating member 31 will move the thread parter and clamp into its 90 rearwardly operating position through the open slot of the front wall of the shuttle box adjacent the feeler slot of the shuttle.

95 In the present instance of the invention, the operating member 31 is connected by a bridge 34 to an arm 35. The shuttle feeler 20 has the usual slotted arm 36 which is connected to the dog 12 for moving it into 100 operative position on call for replenishment of filling, and the arm 35 is connected by a spring 37 to a pin 38 extending laterally from the arm 36, the construction being such 105 that on call for replenishment of filling, the shuttle feeler will be moved towards its rearward position and through the action described, yieldingly move the thread parter and clamp rearwardly to the performance 110 of its thread parting and clamping function.

115 The thread parter and clamp, as indicated in Fig. 4, is normally closed when the parter and clamp is in its frontward position, to thereby hold the filling end leading to the 120 cloth selvage for the action of the temple 125

thread cutter, but on call for replenishment of filling, the thread parter and clamp is opened to engage the filling at the feeler slot of the shuttle when in replenishing position. Any suitable means may be employed for the functional operation of the thread parter and clamp, but, as indicated in the present instance, the thread parter and clamp is opened as it is moved rearwardly to its filling engaging position by means of a trip 39, as indicated in Fig. 2, which acts upon a pin 40 extending from the movable member 29 of the thread parter and clamp, and when the transfer takes place, the movable member 29 of the parter and clamp is closed by means connected to the transfer. Such means, in the present instance of the invention, consists of an actuator 41 which may be secured to the transfer and, as shown, is mounted upon the lever 42 pivotally secured to the transfer at 43 and normally under the influence of a spring 44 to permit yielding movement of the actuator should obstruction occur in the movement of the thread parter and clamp responsive to the operation of the actuator. The parts for operating the parter and clamp as above described may be substantially the same as those shown and described more fully in the application of Alfred E. Stafford, Serial No. 729,670, filed Aug. 2, 1924.

The lay 45 is provided with a shuttle box 46 at the replenishing end thereof, the front wall of which is furnished with an open slot 47 which is adjacent the feeler slot 48 of the shuttle 49 when the latter is in replenishing position. The front wall 50 of the shuttle box may be secured to the lay by the usual securing means, such as the bolts 51, and the slot 47 which is formed in the front wall of the shuttle box is inclined inwardly or towards the cloth selvage. In the present instance this inclination is effected by means of the inclined wall 52, the result being that when the thread parter and clamp is moved to its thread engaging position through the open slot 47 in the front wall of the shuttle box and adjacent the feeler slot 48, it will part or cut the filling end leading to the shuttle eye and on retraction of the thread parter and clamp, the clamped portion leading to the cloth selvage will be moved frontwardly over the top of the shuttle box, as indicated in Fig. 4, and about the cloth selvage as a center, to thereby position the selvage end of the spent filling for the action of the temple thread cutter.

Since the front wall of the shuttle 49 is usually provided with a longitudinal groove 53, Fig. 3, it follows that the cut end of the spent filling will readily pass backward through the shuttle eye when the spent filling carrier or bobbin is ejected from the shuttle, and since the binding effect upon the shuttle

in the box is mainly exerted at the breast or outer portion of the shuttle, the end portion *a* of the filling, Fig. 4, leading to the cloth selvage may be readily moved upwardly and outwardly over the top of the front 70 wall of the shuttle box.

From the described construction, as one good, practical form of the present invention, it will be apparent that the open slot which is formed in the front wall of the 75 shuttle box is positioned to substantially register with the feeler slot of the shuttle when the latter is in replenishing position, thereby obviating the necessity of weakening the shuttle itself by the formation of an 80 extra opening for the entrance of the thread parter and clamp, and upon functional operation of the thread parter and clamp, the end leading to the filling carrier or bobbin will be withdrawn from the shuttle when 85 the spent filling carrier or bobbin is ejected, while the end leading to the cloth selvage will be moved or swung outwardly, over the top of the shuttle box, in the present instance, and will be held by the clamp in position for the action of the temple thread cutter.

While the details of the thread parter and clamp may be widely varied in construction, and the means for actuating the thread 95 parter and clamp may be varied within the true scope of the invention, it is believed that applicant is the first in the art to provide for cutting and clamping the spent filling at 100 a point adjacent the feeler slot of the shuttle when in replenishing position, and withdrawing or swinging the end leading towards the cloth selvage outwardly over the top of the shuttle box to position the end 105 leading to the cloth selvage for the action of the temple thread cutter.

What is claimed is:

1. In a filling replenishing loom, the combination of the lay, a shuttle box at the filling replenishing end thereof, a shuttle having a filling feeler slot and means for engaging the spent filling between the ends of the bobbin opposite the filling feeler slot of the shuttle and withdrawing it over the top of the shuttle box.

2. In a filling replenishing loom, the combination of the lay, a shuttle box at the filling replenishing end thereof, a shuttle having a filling feeler slot, a clamp for engaging the filling between the ends of the bobbin adjacent the feeler slot of the shuttle when in replenishing position and withdrawing it over the top of the shuttle box about the cloth selvage as a center.

3. In a filling replenishing loom, the combination of the lay, a shuttle box at the replenishing end thereof, a shuttle having a filling feeler slot, means for parting the spent filling between the ends of the bobbin adjacent the feeler slot of the shuttle when

in replenishing position, and means for holding the end leading to the cloth selvage and withdrawing it over the top of the shuttle box.

5. 4. In a filling replenishing loom, the combination of the lay, a shuttle box at the replenishing end thereof having its front wall provided with an opening extending downwardly from the top thereof registering with the feeler slot of the shuttle when the shuttle is in replenishing position, and means for removing the spent filling over the top of the shuttle box.

10 5. In a filling replenishing loom, the combination of the lay, a shuttle box at the replenishing end thereof having a front wall provided with an open slot registering with the feeler slot of the shuttle when in replenishing position and inclined towards the cloth selvage, and means for withdrawing the spent filling from said open slot.

15 6. In a filling replenishing loom, the combination of the lay, a shuttle box at the replenishing end thereof having a front wall provided with an open slot registering with the feeler slot of the shuttle when in replenishing position and inclined towards the cloth selvage, and a cutter and clamp for cutting and clamping the spent filling 20 inside the open slot and for withdrawing the end leading to the cloth selvage from said open slot about the cloth selvage as a center.

25 7. In a filling replenishing loom, the combination of the lay, a shuttle box at the replenishing end thereof having its front wall provided with an open slot leading from the edge of the wall and registering with the feeler slot of the shuttle when in

replenishing position, and a clamp for engaging the spent filling at the feeler slot and withdrawing it from the open slot about the cloth selvage as a center. 40

8. In a filling replenishing loom, the combination of the lay having a shuttle box 45 at the replenishing end thereof, the front wall of which has an open slot leading downwardly from the top thereof and registering with the feeler slot of the shuttle when in replenishing position, and means 50 for engaging and withdrawing the spent filling from said open slot over the top of the shuttle box.

9. In a filling replenishing loom, the combination of the lay having a shuttle box 55 at the replenishing end thereof, the front wall of which has an open slot leading downwardly in an inclined direction from the top thereof and registering with the feeler slot of the shuttle when in replenishing 60 position, and means for engaging and withdrawing the spent filling from said open slot over the top of the shuttle box.

10. In a filling replenishing loom, the combination of the lay, a shuttle box at the 65 replenishing end thereof having its front wall provided with an open slot leading from the edge of the wall and registering with the feeler slot of the shuttle when in replenishing position, a thread cutter 70 adjacent the cloth selvage, and a clamp for engaging the spent filling at the feeler slot and withdrawing it from said open slot about the cloth selvage as a center.

In testimony whereof, I have signed my 75 name to this specification.

ALFRED E. STAFFORD.
